UNITED STATES PATENT OFFICE.

W. U. DUDLEY, OF NEW YORK, ASSIGNOR TO HIMSELF AND LAWRENCE
W. CLARK, OF BROOKLYN, N. Y.

IMPROVED HAND-MIRROR.

Specification forming part of Letters Patent No. 92,942, dated July 27, 1869.

To all whom it may concern:

Be it known that I, W. U. DUDLEY, of the city, county, and State of New York, have invented a certain new and useful Improvement in Hand-Mirrors for Toilet Use and other Purposes, the same forming a new and useful article of manufacture; and I do hereby declare that the following is a full, clear, and exact description thereof, reference being had to the accompanying drawings, which form part of this application, and in which—

Figure 1 represents a longitudinal section, at right angles to its face, of a hand toilet glass or mirror constructed according to my improvement; and Fig. 2, a rear view of the base-piece, with its handle-stiffener, constituting one of the details of the same. Fig. 3 is a face view of the mirror complete.

Like letters refer to like parts in all the figures.

My improvement relates to that description of hand-mirrors for toilet use and other purposes in which the frame that holds the glass is elongated at one end to form a handle; or it may be similarly shaped at both ends. The usual mode of constructing such mirrors is to mount the glass in a solid frame or thin block of wood, either naturally of ornamental character or afterward made so by veneering, cut or shaped so as to be of similar contour to the glass, and with a projecting end formed to constitute a handle. Apart from the expense of hand-mirrors so constructed, where a very ornamental appearance is required, there is not only a general want of strength, especially at the neck or junction of the handle with the body, but a great liability to fracture of the glass by the twisting or warping of the wood of which the frame or holder is made. This latter defect is not merely at first or peculiar to any greenness of the wood or newness of the article, when fracture of the glass from such causes frequently occurs, but is induced at any time by sudden and violent changes in the temperature of the atmosphere, exposure to damp, and extreme heat. My improvement obviates such defect, being non absorbent as regards damp, and free from any liability to warp, at the same time combining beauty with strength at a comparatively trifling cost; and the nature of my invention consists in mounting the glass on a base-piece, of wood or other material, hav-

ing a stiffening-extension running into the handle, and embedding the whole in a composition or cement of suitable description that on hardening forms the back edges and outside handle of the mirror.

For the information of others whom it may concern, I will proceed to described the same with reference to the accompanying drawings.

A is the glass; B, a base-piece, of wood or other suitable material, preferably of similar contour to the glass which is designed to be mounted on it, but elongated at one end, which extension, with a strip of metal or other stout material at its back, forms a handle-stiffener, C, to the mirror. This base-piece, with its handle extension or stiffener C, is then laid in a mold or on a block, face downward, with or without the glass A in its place, and a composition or cement of any suitable plastic material applied in sufficient quantity to cover the back and extend beyond the edges of the base-piece B, and so as to surround the handle-stiffener or end extension of the latter, when an upper mold of suitable configuration and having its interior embellished with any ornamental device or devices is pressed down upon the cement, which, when hard or dry, on removing the upper mold and lifting the article from the lower one, constitutes a smooth or finished, and it may be highly ornamental, outer back and handle, D, impervious to damp, exempt from warping, with its consequent liability of fracturing the glass, and preservative of the wooden or other base-piece, which may be of a cheap and rough construction, and that by its end extension, with strengthening-strip at its back, gives not only a general stability to the whole article, but especially stiffens the handle at its junction with the back or body, where it is naturally weakest or most liable to break. The under mold or block may also be embellished with any ornamental device.

The glass may either be laid on a cushion of the lower mold, so as to be embedded at its edges, simultaneously with the forming of the outer back and handle, in the plastic composition or cement, or it may be afterward inserted and restrained to its place on the base piece either by an ornamental bead around the edges of the glass and formed of the same composition or cement of which the outer handle and

back are made, or of different material afterward run round and applied thereto.

As I do not desire to confine myself to any particular composition or cement of which to form the outer handle and back, but design to use any plastic substance or compound of suitable character, it will here suffice to state that a mixture in equal parts (more or less) of paint, sifted sawdust, and shellac forms a very desirable composition for the purpose, and one which readily admits of the color being varied to suit different tastes or demands.

Having now described my improvement, I claim as a new article of manufacture—

A hand or portable toilet-mirror constructed, substantially as described, of a base-piece, B, with its handle extension piece or stiffener C, glass A, and outer back and handle, D, made of any suitable composition or cement, substantially as specified.

W. U. DUDLEY.
